WIRE STITCHING MACHINE

Roy G. Hoffert, Racine, Wis.

Application May 11, 1940, Serial No. 334,561

4 Claims. (Cl. 1—2)

Wire stitching machines constructed substantially like the one disclosed in Patent No. 1,252,011, to Arthur H. Maynard, issued January 1, 1918, are now being manufactured and sold by 5 a corporation with which I am associated. Many of such wire stitching machines are now being used for closing small Cellophane bags containing candies, nuts, etc. It is the present practice to provide each of such bags with an 10 opening above the staple so that a series of bags may be hung on a hook inserted through said openings for displaying the bags and their contents.

The object of my invention is to combine with 15 a wire stitching machine, a punch device for punching an opening in a bag or other article, in position properly spaced above each staple and being automatically operated by the wire stitching machine.

20 More specifically, it is my object to provide a combined wire clincher and punch in the form of a self-contained unit, of simple, durable and inexpensive construction mounted upon the machine base and separated from the stitching 25 mechanism and readily and easily accessible for adjustment or replacement of parts without interfering with or removing any of the stitching mechanism, and further to provide means for operating the combined wire clincher and punch 30 unit by power from the motor transmitted through means separate from and independent of the means for operating the stitcher mechanism, and whereby the relatively delicate and sensitive mechanism of the stitcher will not be 35 affected by the operation of the wire clincher and punch unit.

A further object is to provide combined wire 40 clinching and punching operations properly timed relative to each other and to the stitching mechanism so that during the instant that the bag is gripped and the staple inserted, the wire clinching and punching operations are completed to thereby avoid any movement of the bag during these operations, which might result in failure of one or the other of said operations.

In the accompanying drawing—

Figure 1 shows a side elevation of a complete wire stitching machine embodying my invention, with parts of the base broken away to show the 50 clincher and punch operating mechanism;

Figure 2 shows an enlarged front view of the clincher and punch unit, and a portion of the stitcher head; and

Figure 3 shows a sectional view of same on the 55 line 3—3 of Figure 2.

The staple-forming and inserting mechanism forms no part of my present invention and is not herein fully disclosed. A stitcher substantially like that disclosed in said Patent No. 1,252,011 may be used. It comprises a frame 10, a power 5 shaft 11 having a hand wheel 12 fixed thereto and driven by an electric motor, not shown. That part of the stitching mechanism shown is indicated generally by the numeral 13. A staple like that shown at 14, Figs. 2 and 3, is formed 10 in the stitching mechanism and then pressed down with its free ends projected through the article 15 being stitched. The wire for forming the staples is carried upon the large spool 16. After the staple has been forced through the Cellophane bag or other article I provide means for clinching the staple and at the same time punching an opening in the bag. I have provided the following mechanism for this purpose:

In the base of the frame below the stitching 20 mechanism is a clincher slide 17 mounted for vertical sliding movement within the frame member 18; the heads of the screws 19 overlap the clincher slide 17, as shown in Fig. 2, and hold it against forward movement. Fixed to the 25 upper end of the frame member 18 are two pivot pins 20, and a clincher cam is mounted on each pin. This cam comprises a body portion 21 having a notch at its upper end to receive the pin 20. The cam is substantially triangular in shape, 30 and on both side edges there is a wire-receiving and guiding groove 22. At the wide end of the cam there is a circular recess 23. The cams are within the frame members, and, as shown in Fig. 2, their inner ends are engaged by the clincher 35 slide. As shown in Fig. 3, the clincher slide is formed on its rear face with a recess at 24, into which recess the lower outer corner or arm of the cam will enter when the cam is swung to its upper limit. By forming these cams as shown 40 and described, they may be reversed when one of the grooved edges is worn by the wire.

After the staple is inserted in the bag and there held stationary by the stitcher mechanism, the clincher slide is elevated and this moves both cams upwardly and toward each other, thereby effecting a clinching movement of the staple.

For the purpose of punching a hole in the bag during the instant while the bag is being held 50 and the staple clinched, I have provided a punch-supporting block 25 detachably secured to the back of the clincher slide plate 17 by the set screw 26 and capable of vertical movement in the recess 27 in the frame. The punch 28 is 55

extended through this block 25 and adjustably fixed thereto by the set screw 29.

- On the top of the base at its front end is a combined punch plate and bag guide 30 having a slot 31 in its front edge to receive bags to be stitched and punched and to control the distance to which the bags may be inserted. A punch-receiving opening 32 is formed in the plate 30 in line with the punch.
- 10 It is desirable that the staple and the punched hole be properly spaced from the folded edge of the bag, and for this purpose I have provided, at each side of the base adjacent the slot 31, a regulating plate comprising a body 33 pivoted by 15 the screw 34 to the side of the base and having a laterally extended arm 35 with an upright portion in line horizontally with the slot 31. This plate has an arcuate slot 36 through which an adjusting screw 37 is extended and by which 20 the bag-engaging arm 35 may be fixed in various positions to engage and hold bags in the desired position for receiving the staple and punch.

For actuating the clincher cams and the punch 25 in properly timed relationship with each other and with the stitching mechanism I have provided a lever 36 fulcrumed in the base at 37 and having its front end at 38 extended through an opening 39 in the clincher plate 17. At the rear 30 end of the lever 36 is pivoted a rod 40 extended upwardly through the frame and guided thereby, and at the upper end of the rod is a roller 41 in engagement with a cam 42 on the main shaft 11, which is preferably driven by a motor not shown. A spring 44 is applied to the forward end of the lever 36 to normally move it downwardly.

With the construction described, and assuming that the main shaft 11 is being rotated and the 40 stitching mechanism, not shown, is being operated thereby to force a staple through a bag in the slot 41, then on the instant after the staple is passed through the bag the cam 42 operates the lever 36 and moves the clincher cams and punch upwardly at the same time, thereby completing the operation of clinching the staple and punching the hole in the bag. These clinching and punching operations are performed by mechanisms entirely independent from the stitching mechanism, except that both are powered by the main shaft and in that manner are properly synchronized; also the clincher and punch are spaced apart from the stitching mechanism for

easy accessibility for repair or replacement of parts.

I claim as my invention:

1. In a wire stitching machine, the combination of a base to receive a bag or other article to be 5 stitched, means above the base for forcing a wire staple through a bag, a plate mounted for up and down movement below said base, two clincher cams operatively connected with said plate and moved to and from clinching position with the 10 plate, a punch connected to said plate and movable with it, said base having a punch opening formed therein to cooperate with the punch, and means for operating the plate.

2. In a wire stitching machine, the combination 15 of a base to receive and support a bag or other article to be stitched, a stationary member above said base having a punch opening therein, means above the base for forcing a wire staple through the bag, a sliding clincher plate below said base, 20 two pivoted clincher cams operatively connected with the clincher plate and pivotally supported below said base, and a punch fixed to said clincher plate below said base, and movable with the clincher plate to position for co-operating with 25 the punch opening above the base.

3. In a wire stitching and punching machine, the combination of a base to support a bag or other article to be stitched, a member overlapping said base and having a punch opening, a clincher 30 slide plate mounted for vertical movement below the base, clincher cams operatively connected to the slide plate, a punch block fixed to the slide plate, means for guiding said block, and a punch fixed to the block for cooperating with said member having a punch opening.

4. In a wire stitching machine, the combination of a base to receive a bag or other article to be stitched, means above the base for forcing a wire staple through the bag, a plate mounted for up 40 and down movement below said base, two clincher cams operatively connected with said plate and moved to and from clinching position with the plate, a punch connected to said plate and movable with it, said base having a punch opening 45 formed therein to cooperate with the punch, and means for operating the plate, said means comprising a power shaft, a cam operated thereby, a lever fulcrumed to the frame, means for tilting the lever by said cam, the forward end of the 50 lever being connected to said plate, whereby the clinching and punching operations will be operated in timed relation to said shaft.

ROY G. HOFFERT.
